Primary Examiner — Karen E Eldridge Powers*(74) Attorney, Agent, or Firm* — Gardner Groff Greenwald & Villanueva, PC(57) **CLAIM**

The ornamental design for sports shorts, as shown and described.

DESCRIPTION

FIG. 1 is a perspective view of sports shorts according to the present invention.

FIG. 2 is a front view of the sports shorts of FIG. 1.

FIG. 3 is a rear view of the sports shorts of FIG. 1.

FIG. 4 is a right side view of the sports shorts of FIG. 1.

FIG. 5 is a left side view of the sports shorts of FIG. 1.

FIG. 6 is a top view of the sports shorts of FIG. 1; and,

FIG. 7 is a bottom view of the sports shorts of FIG. 1.

FIGS. 1-7 show the sports shorts “as worn” in the shape they have when worn by a person.

The two broken lines at the top of the waist of the claimed design are stitching.
